United States Patent Office

Des. 202,841
Patented Nov. 9, 1965

202,841

AIRPLANE

Robert W. Allred, Bellevue, and Fred W. Clayton, Maple Valley, Wash., assignors to The Boeing Company, Seattle, Wash., a corporation of Delaware

Filed Nov. 23, 1964, Ser. No. 32,738

Term of patent 14 years

(Cl. D71—1)

Fig. 1

Fig. 2

Fig. 6

FIGURE 1 is a three-quarters front perspective view taken from the top.

FIGURE 2 is a three-quarters rear perspective view taken from the bottom.

FIGURES 3, 4 and 5 are front, rear and side elevation views respectively.

FIGURE 6 is a top plan view of the new airplane design.

The dominant features of our design are shown in solid lines in the drawings.

We claim:

The ornamental design for an airplane, substantially as shown and described.
